MOLD FOR BATTERY GRIDS

Harry B. Lockwood, Cleveland Heights, Ohio, assignor to Willard Storage Battery Company, Cleveland, Ohio, a corporation of West Virginia

Application August 4, 1938, Serial No. 223,069

1 Claim. (Cl. 22—153)

This invention relates to improvements in molds for battery grids and has reference particularly to a provision in the construction of a mold for storage battery grids which facilitates the escape of air from the mold as the metal is poured into it, and which by permitting rapid filling of the mold makes feasible the use of lead alloy metal with a smaller proportion of antimony and at a lower pouring temperature than has been possible heretofore.

One of the objects of the invention therefore is the provision of a mold of the character stated which promotes rapid filling of the cavity by the molten metal.

Another object is the provision of a mold which will permit the use of lower cost metal.

Another object is the provision of a mold which will permit the pouring of a given non-ferrous metal at lower temperature than has been possible heretofore.

Other objects and features of novelty will appear as I proceed with the description of that embodiment of the invention which, for the purposes of the present application, I have illustrated in the accompanying drawings, in which

Fig. 1 is a fragmental elevational view of one end of a mold for storage battery grids.

Fig. 2 is a fragmental elevational view on a larger scale of the inner surface of one of the mold plates or halves.

Fig. 3 is a transverse sectional view taken substantially on the line 3—3 of Fig. 1 on a considerably larger scale.

Figs. 4 and 5 are elevational views of the inner surfaces looking in the direction of the arrows 4—4 and 5—5 of Fig. 1.

Fig. 6 is a fragmental view similar to Fig. 3 but on a still larger scale.

Fig. 7 is a vertical sectional view of the two mold plates, the view corresponding to the line 7—7 of Fig. 2.

Fig. 8 is a fragmental view on a still larger scale of a portion of the section illustrated in Fig. 7.

In Figs. 1 and 2 mold plates or halves are indicated at 10 and 11, with their backing plates 12 and 13 respectively. Means for locking the mold parts together is indicated at 14 and 15, and a chute for discharging the castings after the mold has been opened is indicated at 16.

The drawings show a mold for casting two grids simultaneously, but it should be understood that this is for illustrative purposes only as the invention may be applied to molds for casting single grids or for casting a plurality of grids

greater than two. When the mold halves are brought together close contact is effected between the accurately finished plane surfaces surrounding the mold cavity, these surfaces comprising parts 17, 18 and 19 in mold plate 10, and 17', 18' and 19' in mold plate 11. Throughout the space in which the body of the grid is to be cast there are of course small plane surfaces 9 of approximately rectangular form which correspond with the spaces between the bars of the 10 grid. There are also slender plane surfaces 20 and 21 in plate 10, and 20' and 21' in plate 11, which are for the purpose of providing breakage lines by means of which the two grids may be readily broken apart after the casting is 15 formed.

The cavities in the two mold plates are flared at the top as indicated at 22 and 22' to provide a trough into which the molten metal may be poured. When the metal enters the mold 20 proper it must descend between small spaced vertical barriers 23 and 24, 24' which serve to evenly distribute the metal across the entire width of the mold.

In accordance with the preferred form of my 25 invention the mold plate 11 is formed in the usual way to include approximately one-half of the mold cavity. The mold plate 10 includes the other half of the cavity, but it departs from the usual construction in that an undercut 25 is machined or ground into its surface, this undercut extending throughout nearly the entire area of the cavity for each individual grid. The outer edges of the undercut for each grid are indicated at 26 in Figs. 2 and 4. In forming this undercut 30 35 the inner surface of the mold plate is machined or ground down to a small extent only, that is to a depth of the order of one and one-half thousandths of an inch.

Vent holes 27 are provided in one or the other 40 or both of the plates 10 and 11, but preferably in the plate 11 exclusively, these vent holes being connected with vent openings 28 in the backing plate 13.

The making of castings by the use of my improved mold involves the same procedure as is followed in the use of conventional molds now in common use, that is to say after the mold surfaces have been cleaned they are coated with a heat insulating mold coating applied by a spray 45 gun and indicated at 29 in the drawings. Then a steel scraper is used to remove all of the coating on the plane or meeting surfaces of the two plates, the coating remaining in the cavities of both plates and also in the undercut parts of 50 55

plate 10. When the two mold plates are put together a very thin relief 30 is left between the coating 29 on the undercut portions and the scraped plane surfaces of the mold plate 11, the 5 previously stated depth of the undercut, that is one and one-half thousandths of an inch approximately, being such as to leave the desired relief after the undercut surface is coated. This thin relief is sufficient to permit air to escape to the 10 vent holes 27, but is not sufficient to permit the flow of molten metal therethrough. In fact the metal is chilled and solidifies immediately upon striking the relief. The air displaced by the 15 molten metal flowing down through the mold interstices is easily dispelled however through this relief and the flow of the metal is therefore greatly facilitated. Because of this more rapid flow a metal of lower antimony content may be used, or the same metal may be used at a some- 20 what lower temperature. By way of example it may be noted that whereas a common practice in the casting of grids for storage batteries prior to the present invention was to pour a lead alloy containing 12% antimony at 1100° F., a 9½% 25 antimony alloy may be poured in my improved mold at from 920° F. to 1050° F.

Although I prefer to undercut mold plate 10 only, it is within the spirit of the invention to form the undercut partly in one plate and part-

ly in the other, in which event the relief would be between two coated surfaces instead of between a scraped plane surface and a coated surface. It is also within the spirit of the invention to undercut plate 11 exclusively rather than 5 plate 10, in which event the undercut and the vent holes 27 would all be in the same plate.

Variations from the described structure may be employed. Accordingly I desire it to be understood that the scope of the invention is to be 10 regarded as defined exclusively by the appended claim rather than by the foregoing description or the accompanying illustrations.

Having thus described my invention, I claim:

In a mold for casting storage battery grids, a 15 pair of mold plates having matching mold cavities in their adjacent relatively plane faces, one of said plates being undercut from its plane meeting face throughout a large part of its surface, the cavities of said mold and said undercut 20 surface being coated with a heat insulating mold coating, the depth of the undercut being uniform and such that when so coated a relief will be formed between the mold plates intermediate said cavities small enough to prevent molten 25 metal from entering, and one of said mold plates having vent passages connecting with said relief.

HARRY B. LOCKWOOD.
